SHADE OR GLOBE SUPPORTING MEANS

Filed June 5, 1922

UNITED STATES PATENT OFFICE.

WILLIAM L. KORNFELD AND ARTHUR R. ENGLANDER, OF CLEVELAND, OHIO, AS
SIGNORS OF ONE-FIFTH TO ARTHUR P. GUSTAFSON, OF CLEVELAND, OHIO.

SHADE OR GLOBE SUPPORTING MEANS.

Application filed June 5, 1922. Serial No. 565,957.

To all whom it may concern:

Be it known that we, WILLIAM L. KORNFELD and ARTHUR R. ENGLANDER, citizens of the United States, residing at Cleveland, 5 in the county of Cuyahoga and State of Ohio, have invented a certain new and useful Improvement in Shade or Globe Supporting Means, of which the following is a full, clear, and exact description, reference being had to the accompanying drawings.

This invention relates to a shade or globe supporting means for use with electric lights, and has for its objects to provide 15 means which may be readily applied to a standard type of socket and firmly locked thereto so as to effectually support the weight of a shade or globe; to provide a device of this character which is neat and 20 attractive of appearance and which conceals a part of the socket and so harmonizes with the portion revealed as to produce a pleasing effect; to combine with a shade holder of the foregoing nature an adapter 25 which may be attached to the holder in the same manner as a shade is attached thereto and which, in turn, incorporates globe sustaining means; and to constitute of said adapter a reflector whereby the efficiency 30 of the light is increased.

The foregoing objects with others hereinafter appearing are attained in the embodiment of the invention illustrated in the accompanying drawing wherein Fig. 1 is a 35 sectional side elevation of a lighting fixture equipped with the device of our invention showing it supporting a globe in proper relation to an electric lamp; Fig. 2 is a side elevation, at right angles to Fig. 1, of the shade holder applied to the lamp socket; and Fig. 3 is a plan view of what is shown in Fig. 2.

An electric lamp of usual type is represented at 1 and the same is supported from 45 a socket 2. The socket is of common form, comprising a shell 1' that telescopes at its upper end into an enlargement 3 of a cap 4 which is suspended, through its boss 5, from a wire concealing tube 6.

Our improved shade holder consists of a 50 bell shaped casing 7 which is of a diameter at its upper end to fit snugly about the upper end of the shell 1' and abut the lower edge of the enlargement 3. A bail 8 is connected, by suitable pivot means 9,

to the opposite sides of the casing 7 and it is adapted to be swung up over the cap 4 and embrace the boss 5, the bail having a notch 10 for the accommodation of said boss. The side branches of the bail 8 are 60 enlarged laterally to provide wings 11 that are formed to snugly embrace the enlargement 3, the forward edges of the wings being flared outwardly slightly, as indicated at 12 in Fig. 3, to facilitate the bail's slipping over the enlargement. The casing 7 is notched at 13 for the reception of the shank of a key 14; and at its lower edge is equipped with shade attaching means which are shown, in the present instance, 70 as screws 15 that are threaded through the edge portion of the casing.

It will be readily understood that a shade (not shown) may be applied to the holder by inserting the neck of the shade upwardly 75 into the lower end of the casing 7 and projecting the screws 15 inwardly into engagement with the neck, in accordance with common practice.

In the same manner an adapter 20 is attached to the holder. This adapter is shown as substantially frusto-conical in shape, terminating at its upper end in a neck 21 and at its lower end in a vertical flange 22 through which globe supporting means in 80 the form of screws 23 are extended, the flange being shown as provided with bushings 24 through which the screws are threaded. This adapter is particularly suitable for use with a special form of globe 90 which in the drawing is designated generally by the numeral 25. The globe of itself constitutes no part of our invention. It has a neck 26 at its upper end that is adapted to be received within the flange 95 22 and to be engaged by the screws 23. As to contour, the globe is curved outwardly and downwardly below the neck 26 a suitable distance to a point designated by the line A—A, and for a suitable distance below 100 this point to a point designated by line B—B it converges; and after bulging outwardly rather abruptly below the line B—B, the globe again converges to effect a sort of semi-spherical shape. Above the line A—A, 105 and below the line B—B, the globe is translucent; while between said lines it is transparent or clear. This results in a sort of semi-indirect lighting effect, certain rays from the lamp being reflected downwardly 110

by the portion of the globe above line A—A through the clear portion between lines A—A and B—B, while other rays filter through the translucent portion below the latter line. In a substantially horizontal direction, of course, direct rays escape through the clear portion of the globe. While it is desirable to soften the rays descending from the lamp through the translucent lower portion of the globe, too much filtering of the light is extravagant and objectionable and to increase the efficiency of the light penetrating the lower portion of the globe to a very considerable extent we finish the inner surface of the adapter 20, particularly the frustoconical portion thereof, to a very high brilliancy, as by silver plating and polishing in the manner of finishing reflectors of usual type, so that the rays which would otherwise be lost are redeemed and cast downwardly, the majority of them falling through the lower portion of the globe while some are cast off through the transparent zone between the lines A—A and B—B.

It is clearly within the scope of our invention to alter the shape of that portion of the adapter 20 hereinbefore referred to as frusto-conical, it being apparent that such portion may be curved axially and, if desired, given the contour of a parabola.

Also, the adapter and shade holder may be constructed as a single unit without departing from the spirit of our invention. Such modifications as those suggested are so obvious as to make specific illustration of them unnecessary.

Having thus described our invention, what we claim is:

40. 1. For use with a lamp socket having a circumferential enlargement, a globe holder comprising a casing designed to fit over the lamp receiving end of the socket and concealed the same and have its inner end engaged with said enlargement, and a bail hingedly connected to opposite sides of the casing and adapted to be swung over the end of the socket remote from the lamp receiving end for positively holding the casing against withdrawal from the socket, the casing being provided with globe attaching means.

2. A shade holder for use with a lamp socket having a circumferential enlargement, the holder comprising a casing adapted to be slipped over the lamp receiving end of the socket with its inner ends in engagement with the enlargement, while its opposite end is provided with shade attaching means, and a bail pivotally connected to opposite sides of the casing and arranged to be swung over the end of the socket re-

mote from the lamp receiving end thereof, the opposite branches of the bail having parts frictionally engaging the enlargement 65 of the socket to hold the bail in operative position.

3. A shade holder for use with a lamp socket having a circumferential enlargement and a neck spaced therefrom in a direction away from the lamp receiving end of the socket, the holder comprising a casing adapted to be slipped over the lamp receiving end of the socket with its inner end in engagement with the enlargement, 70 while its opposite end is provided with shade attaching means, and a bail pivotally connected to opposite sides of the casing, the bail having a notch for the reception of the neck of the socket when the bail is 80 swung into operative position, the opposite branches of the bail having parts frictionally engaging the enlargement of the socket to hold the bail in operative position. 85

4. A shade holder for use with a lamp socket having a circumferential enlargement intermediate its ends and terminating at its inner end in a neck, a casing adapted to be slipped over and conceal the outer end of the socket and to have its inner end in engagement with the aforesaid enlargement, while its opposite end is provided with shade attaching means, and a bail pivotally connected at its ends to diametrically opposed parts of the casing and having at its middle a neck embracing notch adapted to receive the neck of the socket when the bail is in operative position, the branches of the bail having laterally extending wings which are formed to embrace the enlargement of the socket thereby to hold the bail in operative position. 100

5. A shade holder for use with a lamp socket having a circumferential enlargement and provided at its inner end with a neck, a substantially bell-shaped casing adapted to fit over and conceal the lamp receiving end of the socket and arranged to have one of its ends abut against the aforesaid enlargement, the opposite end of the shell incorporating shade attaching means, and a bail pivotally connected at its ends to diametrically opposed parts of the casing and having a notch which embraces the neck of the socket when the bail is in operative position, the bail being formed so as to cooperate with the socket in such manner as to be held by frictional engagement therewith in operative position. 115

In testimony whereof, we hereunto affix our signatures.

WILLIAM L. KORNFELD.
ARTHUR R. ENGLANDER.
